UNITED STATES PATENT OFFICE.

HERBERT ETHERIDGE, OF WIMBLEDON PARK, ENGLAND, ASSIGNOR TO THE BAR-LOCK TYPEWRITER COMPANY, LIMITED, OF LONDON, ENGLAND.

PLATEN-CARRIAGE HOLDER FOR TYPE-WRITERS.

1,172,016.

Specification of Letters Patent.

Patented Feb. 15, 1916.

Application filed February 16, 1915. Serial No. 8,541.

To all whom it may concern:

Be it known that I, HERBERT ETHERIDGE, a subject of the King of England, residing at Wimbledon Park, in Surrey, England, **5** have invented certain new and useful Improvements in Platen-Carriage Holders for Type-Writers, of which the following is a specification.

This invention relates to platen-carriage **10** holders for typewriters, wherein the holder with the carriage is bodily detachable from the machine base by the operator without the use of tools. Such carriage-holders have already been made in which the spring driving-barrel for the carriage has been mounted on the holder so that the removal of the holder from the machine can be effected without disconnecting the spring-barrel from the carriage. The other mechanisms which **15** coöperate with the carriage, such for example as the escapement, have, however, been mounted on the base of the machine with the result that such mechanisms cannot be tested in relation to their operation with **20** the carriage except when assembled on the machine where the mechanisms are not easily observed in operation or easy of access for adjustment; moreover, when the escapement is mounted on the base and the **25** spring-barrel on the holder, the carriage becomes freed from the escapement-mechanism as the holder is lifted from the base and thus having no restraining device flies with the full force of its driving-mechanism **30** to the limit of its movement to the left of the holder which is inconvenient and may sometimes cause damage. It has been proposed to mount the driving spring with the **35** escapement mechanism, line-locking mechanism, margin stop, and bell, on a plate which supported the platen-carriage, but this plate was screwed to columns on the machine base so as to constitute part of the frame of the **40** machine and could not be detached by the operator without the use of tools.

One feature therefore of the present invention consists in mounting the escapement mechanism as well as the spring-barrel on the platen-carriage holder so that these parts **45** come away as one piece with the holder when this is bodily removed, the arrangement being such that the holder can be removed and reattached by the operator without the use of tools.

50 The invention further relates to the

mounting of other parts on the holder which parts also coöperate directly with the platen-carriage and therefore require adjustment in relation thereto.

In the accompanying drawings which **55** illustrate one method of carrying out this invention:—Figure 1 is a plan of the carriage-holder with the various parts in position thereon; Fig. 2 is a section on the line 2—2 of Fig. 1, part of the bearing-member **60** of the holder being broken away for the sake of clearness; Fig. 3 is a section on the line 3—3 of Fig. 1; Fig. 4 is a section on the line 4—4 of Fig. 1; Fig. 5 is a detail of the escapement-mechanism; Fig. 6 is a detail of **65** the locking-mechanism; and Fig. 7 is a side-elevation of the platen-carriage.

The same letters indicate the same parts throughout the drawings.

The platen-holder comprises the usual **70** pair of parallel bearing-members or runners A connected by transverse-members A¹ which carry catches A² for securing it to the base of the machine. The base of the machine is usually provided with studs, indicated at *a* which are headed or notched to receive the catches A² and thus lock the holder firmly to the base. The spring-barrel B is carried by a base-plate B¹ made fast to the runners A and the arbor of the barrel **75** carries a toothed wheel B² which when the carriage is in place meshes with a rack X, Fig. 7, supported on the under-side of the carriage Y. All these parts are the same as have been already employed. The base **80** B¹ in the present case is, however enlarged to carry the escapement-mechanism, the escape-wheel whereof is indicated at C. The escape-wheel spindle also carries a toothed wheel C¹ whose periphery on one side is in line with that of the wheel B², so that the wheels B² and C¹ can both engage the rack X.

The escapement-mechanism may be of any **90** convenient form, that shown being well known and as it constitutes no part of the present invention it need not be further described except that the dogs D may be indicated as pivoted on a frame D¹ also carried on the base-plate B¹. The dogs have a **95** tail-piece D² which, when the holder is in position on the base, lies under a bail-member indicated at Z, Fig. 5, carried by the base of the machine and operated by the keys and letter-spacing bar. It will be seen **100** 110

that by mounting this escapement-mechanism on the holder, the further advantage over those already referred to is obtained that when the holder is lifted off the base, 5 the carriage does not fly to one end as it does in machines where the driving-barrel is on the holder but the escapement-mechanism on the base. With such arrangement, it follows that directly the rack of the platen-carriage is disengaged from the escapement-mechanism by lifting the holder and carriage off the base, there is nothing to restrain the pull of the driving-barrel, and so 10 the carriage is moved with the full force of the driving-mechanism to the limit of its travel to the left of the machine.

The mechanism for stepping the carriage back space-by-space is also shown as mounted on the holder. This mechanism is of a 20 form well-known and no claim is made therefor *per se*. It comprises a pawl E pivoted at E¹ on a link E² which link is pivoted to a support on the plate B¹ at E³. The tail end of the pawl is connected by a 25 link E⁴ to an arm E⁵ on a rock-shaft E⁶. The rock-shaft is controlled by a spring E⁷ which always tends to keep it in such position that the pawl is thrown forward clear of the wheel C¹ as shown in Fig. 1, but on the 30 rock-shaft is an operating-handle E⁸, which, when depressed, swings the rock-shaft in such direction that the arm E⁵ is raised, and the pawl E is thus first swung into engagement with the wheel and then drawn 35 backward to the left of Fig. 1, so that the wheel is rotated one tooth and the carriage is thus stepped back one space. The rock-shaft E⁶ is supported in any convenient manner in bearings on the under-side of the 40 front bearing-member A of the holder.

A known form of brake-mechanism for tabulating is also mounted on the plate B¹ of the holder. This comprises a toothed wheel F which normally is held clear of the 45 rack X on the carriage Y. The rotation of the wheel is retarded by a spring F¹, Fig. 3, in the usual manner and the wheel with its spring is carried on a stud mounted on a frame F² which can swing about a pivot 50 F³. The frame is spring-controlled to keep the wheel clear of the rack X, but an operating-member on the base of the machine is arranged to contact with any convenient part operatively connected with the frame 55 F² to swing the wheel forward into mesh with the rack X when the tabulating lever is pressed.

The margin- and paragraph-stop members are also shown mounted on the holder. 60 The rocking-lever G constitutes the margin-stop member and is pivoted at G¹ to the rear bearing-member A of the holder. The right-hand end of the lever, Fig. 2, depends, so that it can be operated by a key mounted 65 on the base, and the left-hand end of the

lever is up-turned and engages the usual margin-stop on the carriage.

A spring G² connected at one end to an arm G³ on the margin-member and at the other end to a part carried by the bearing-member A of the holder, tends to keep the left-hand end of the margin-member raised. The hole through which the pivot G¹ of the margin-member projects is slotted which gives the margin-member freedom for a certain amount of endwise movement, but the spring G² normally not only keeps the left-hand end raised but keeps the member to the limit of its endwise movement to the right of Fig. 2.

Pivoted at H¹ on the holder-member A, is a paragraph-stop member H. Its left-hand end is upwardly turned at H² and co-operates with the usual stop on the platen-carriage, but its right-hand end carries a pin H³ which lies beneath the margin-stop member G. It thus follows that when the right-hand end of the margin-stop member G is raised, its left-hand end will be depressed and coming into contact with the pin H³ will cause the left-hand end of the paragraph-stop to be raised for engagement with the stop on the carriage. The upturned left-hand end of the member G is engaged by the platen-carriage as the latter nears the left-hand end of its movement, and further movement of the carriage draws the member G endwise to the left.

The endwise movement of the member G is employed to operate a locking-device for the dogs. Such locking devices are well-known, but the present one is adapted for mounting on the holder so that it may come away with the dogs when the holder is removed from the machine. This locking-device comprises a bent bar J which extends through the upturned sides of the plate B¹, and when advanced for locking, lies beneath the bail-member Z but normally lies free of the same, as shown in Fig. 4. The bar J is 100 operatively connected with the margin-stop member G by a lever J¹ (Fig. 6) pivoted at J², which lever is moved by a second lever J³ also pivoted at J². The second lever has an upwardly turned ear J⁴ which lies on one 110 side of the lever J¹ and it has an arm J⁵ which lies in the path of the arm G³ on the margin-stop member G. The pivot-pin J² is surrounded by a spring J⁶ connected to the arm J⁵ and the torsional action of the 120 spring normally keeps the arm J² and also the arm J¹ in the position shown in Fig. 1, so that the rod J is withdrawn from the locking position. The arms J¹, J² are connected by a spring J⁶ so that if the arm J³ 125 is moved counter-clockwise, the arm J¹ will be made to follow it by means of the spring connection J⁶. As the platen-carriage comes to the end of its travel to the left of the machine, it catches the upwardly-turned left- 130

hand end of the margin-stop member G and pulls this to the left against the action of the spring G². The arm G³ on the member G, thus comes into contact with the arm J³ 5 on the lever J³ so that this is moved counter-clockwise in Fig. 1, and carrying the arm J¹ with it advances the rod J. If, as sometimes happens, the bail Z should be partly down, as shown in dotted lines Fig. 10 4, the end of the bar J will strike the bail and the arm J¹ will thus be prevented from moving with the arm J³, but no breakage of the parts will occur because the spring J⁶ allows the lever J¹ to remain behind. 15 The lever J³, however, will remain advanced so that as soon as the bail is raised, the bar J will shoot into position beneath it. When the arm J³ is allowed to return under the control of its spring J¹ it carries the arm J³ 20 back with it by the ear J⁴.

The bell K is also mounted on the plate B¹ so as to come away with the holder and the hammer K¹ for striking it is pivoted to a pin K² carried by the rear operating-member A of the holder. The hammer is controlled by a spring K³ and has a tail-piece K⁴ which is tripped in the usual manner by the carriage as it nears the end of its travel to the left.

30 It will be seen from the above description that all the parts which coöperate in a direct way with the platen-carriage are thus mounted on the holder in such manner that they can be operated in relation to the carriage without placing the holder and carriage on the machine, so that all these parts can be readily observed and adjusted to accurately perform their various functions.

40 What I claim as my invention and desire to secure by Letters Patent is:—

1. In a typewriter detachable platen-carriage holder, the combination of, two parallel runners (A) for the platen-carriage, 45 transverse members connecting these runners, means whereby the operator without tools can detach the runners with their transverse members from the machine or attach them thereto, a spring driving-barrel mounted between the runners on one of the transverse members as viewed in plan, an escapement-wheel mounted on one of the transverse members of the runners and between the runners as viewed in plan, a toothed driving-wheel movable with the escapement-wheel which driving-wheel gears with the carriage, and dogs for the escape-wheel mounted on one of the transverse members between the runners as viewed in plan, so that all these parts can be operatively tested in relation to the carriage-holder without placing the holder and carriage on the machine base, substantially as set forth.

65 2. In a typewriter detachable platen-car-

riage holder, the combination of, two parallel runners (A) for the platen-carriage, transverse members connecting these runners, means whereby the operator without tools can detach the runners with their transverse members from the machine or attach them thereto, a spring driving-barrel mounted between the runners on one of the transverse members as viewed in plan, an escapement-wheel mounted on one of the transverse members of the runners and between the runners as viewed in plan, a toothed driving-wheel movable with the escapement-wheel which driving-wheel gears with the carriage, dogs for the escape-wheel mounted on one of the transverse members between the runners as viewed in plan, a margin-stop member (G) mounted on the carriage-holder in position to coöperate with the usual stop on the platen-carriage and a 70 key on the base, and a paragraph-stop member (H) on the carriage-holder and operatively connected with the margin-stop member (G) to be moved into operative position by the movement of the latter to the inoperative position, so that all these parts can be operatively tested in relation to the carriage-holder without placing the holder and carriage on the machine-base, substantially as set forth.

3. In a typewriter detachable platen-carriage holder, the combination of, two parallel runners (A) for the platen-carriage, transverse members connecting these runners, means whereby the operator without tools can detach the runners with their transverse members from the machine or attach them thereto, a spring driving-barrel mounted between the runners on one of the transverse members as viewed in plan, an escapement-wheel mounted on one of the transverse members of the runners and between the runners as viewed in plan, a toothed driving-wheel movable with the escapement-wheel which driving-wheel gears with the carriage, dogs for the escape-wheel mounted on one of the transverse members between the runners as viewed in plan, a rocking-shaft (E⁶) mounted on the carriage-holder and extending from one end toward the center of the holder, a back-spacing pawl (E) mounted on the holder and arranged to engage the teeth of the driving-wheel carried by the escapement-wheel, and operative connection between the pawl and the rocking-shaft whereby rocking of the shaft causes the pawl to turn the wheel engaged by it one tooth at each operation, all these parts being so arranged that they can be operatively tested in relation to the carriage-holder without placing the holder and carriage on the machine-base, substantially as set forth.

4. In a typewriter detachable platen-carriage holder, the combination of, two par-

parallel runners (A) for the platen-carriage, transverse members connecting these runners, means whereby the operator without tools can detach the runners with their transverse members from the machine or attach them thereto, a spring driving-barrel mounted between the runners on one of the transverse members as viewed in plan, an escapement-wheel mounted on one of the transverse members of the runners and between the runners as viewed in plan, a toothed driving-wheel movable with the escapement-wheel which driving-wheel gears with the carriage, dogs for the escape-wheel mounted on one of the transverse members between the runners as viewed in plan, and a bell-mechanism and bell carried by the holder, so that all these parts can be operatively tested in relation to the carriage-holder without placing the holder and carriage on the machine-base, substantially as set forth.

5. In a typewriter detachable platen-carriage holder, the combination of, two parallel runners (A) for the platen-carriage, transverse members connecting these runners, means whereby the operator without tools can detach the runners with their transverse members from the machine or attach them thereto, a spring driving-barrel mounted between the runners on one of the transverse members as viewed in plan, an escapement-wheel mounted on one of the transverse members of the runners and between the runners as viewed in plan, a toothed driving-wheel movable with the escapement-wheel which driving-wheel gears with the carriage, dogs for the escape-wheel mounted on one of the transverse members between the runners as viewed in plan, a locking-bar carried by the holder and movable into position to lock the escapement mechanism, and means operatively connecting the locking-bar with the carriage as the latter arrives at the end of its travel to the left of the machine, so that all these parts can be operatively tested in relation to the carriage-holder without placing the holder and carriage on the machine-base, substantially as set forth.

50 6. In a typewriter detachable platen-carriage holder, the combination of, two parallel runners (A) for the platen-carriage, transverse members connecting these runners, means whereby the operator without tools can detach the runners with their transverse members from the machine or attach them thereto, a spring driving-barrel mounted between the runners on one of the transverse members as viewed in plan, an escapement-wheel mounted on one of the transverse members of the runners and between the runners as viewed in plan, a

toothed driving-wheel movable with the escapement-wheel which driving-wheel gears with the carriage, dogs for the escape-wheel mounted on one of the transverse members between the runners as viewed in plan, a locking-bar carried by the carriage-holder and movable into position to lock the escapement mechanism, an arm (J¹) pivoted by one of its ends to the holder and at the other end to the locking-bar, a second arm pivoted by one of its ends to the holder and having a lip providing a one-way engagement with the other arm, a spring connection which keeps the lip of the one arm in engagement with the other, and means to provide operative connection between the platen-carriage as it comes to the end of its travel to the left of the machine and the arm with the lip in such manner as to tend to move the lip away from the arm engaged by it, all substantially as and for the purpose set forth.

7. In a typewriter detachable platen-carriage holder which is bodily removable from the machine base, the combination of, a spring driving-barrel mounted on the holder, driving connection between the barrel and the platen-carriage, an escapement-wheel mounted on the holder, a toothed driving-wheel movable with the escapement wheel which driving-wheel gears with the carriage, dogs for the escape-wheel mounted on the holder, a locking-bar carried by the holder and movable into position to foul the bail, a margin-stop member (G) pivoted on the holder and so arranged that in addition to engagement by the margin-stop on the platen-carriage it can be engaged by the platen-carriage as it nears the end of its travel to the left of the machine, said member having its pivot-hole slotted so that it can be moved with the carriage as well as rock about its pivot, a spring which normally keeps one end of the member in position to engage the carriage and also keeps it with one end of its slot up against its pivot, and yielding operative connection between this member and the locking bar so that when the member moves endwise the locking-bar is yieldingly advanced to the locking position, so that all these parts can be operatively tested in relation to the carriage-holder without placing the holder and carriage on the machine base, substantially as set forth.

In testimony whereof I have signed my name to this specification in the presence of two subscribing witnesses.

HERBERT ETHERIDGE.
